UNITED STATES PATENT OFFICE

127,689

DESIGN FOR AN AUTOMATIC CUT-OFF DEVICE FOR DISPENSING APPARATUS

Henry F. Soper, East Orange, N. J., assignor to
Neptune Meter Company, a corporation of New
Jersey

Application March 24, 1941, Serial No. 99,813

Term of patent 14 years

To all whom it may concern:

Be it known, that I, Henry F. Soper, a citizen
of the United States, residing at East Orange,
county of Essex, and State of New Jersey, have
invented a new, original, and ornamental Design
for an Automatic Cut-off Device for Dispensing
Apparatus, of which the following is a specific-
cation, reference being had to the accompanying
drawing, forming a part thereof, in which:

Figure 1 is an end view of the automatic cut-
off device;

Figure 2 is a plan view of the device; and
Figure 3 is a side view of the device, showing
my new design.

I claim:

The ornamental design for an automatic cut-
off device for dispensing apparatus, as shown.

HENRY F. SOPER.
